UNITED STATES PATENT OFFICE.

HARRY McCREARY, OF INDIANA, PENNSYLVANIA.

DESIGN FOR A NONSKID TIRE.

Application filed February 20, 1923. Serial No. 5,228. Term of patent 3½ years.

To all whom it may concern:

Be it known that I, HARRY McCREARY, a citizen of the United States, residing at Indiana, in the county of Indiana and State of Pennsylvania, have invented a new, original, and ornamental Design for a Non-skid Tire, of which the following is a specification, reference being had to the accompanying drawing, forming part thereof.

Figure 1 is a plan view; and Fig. 2 is a

perspective view of a portion of a non-skid tire, showing my new design.

I claim:

The ornamental design for a non-skid tire, as shown.

HARRY McCREARY.
